UNITED STATES PATENT OFFICE

151,028

DESIGN FOR A BOTTLE

William Blitzstein, Chicago, Ill., assignor to Sunset, Incorporated, Chicago, Ill., a corporation of Illinois

Application November 18, 1946, Serial No. 134,843

Term of patent 14 years

(Cl. D58—8)

To all whom it may concern:

Be it known that I, William Blitzstein, a citizen of the United States, residing at Chicago, county of Cook, State of Illinois, have invented a new, original, and ornamental Design for a Bottle, of which the following is a specification, reference being had to the accompanying drawings, forming a part thereof.

I claim:

The ornamental design for a bottle, as shown.

WILLIAM BLITZSTEIN.
